UNITED STATES PATENT OFFICE.

ARTHUR C. HOWE, OF ENUMCLAW, WASHINGTON.

VEHICLE TOY.

Application filed January 21, 1924. Serial No. 687,628.

To all whom it may concern:

Be it known that I, ARTHUR C. Howe, a citizen of United States, residing at Enumclaw, in the county of King and State of Washington, have invented certain new and useful Improvements in Vehicle Toys, of which the following is a full, clear, and exact description.

My invention relates to improvements in vehicle toys of the type for use and amusement of children, and has for its object to provide a device which will not only furnish amusement and pleasure, but will also at the same time provide a source of exercise 15 through its manner of operation.

A further object of the invention resides in the construction of such a device of relatively few parts simply united so as to provide a self-propelled vehicle which will 20 withstand the rough treatment to which it is necessarily subjected. Also, the simplicity of construction renders it a relatively inexpensive toy.

Other objects and advantages of the invention will be apparent from the following description when taken in connection with the accompanying drawings in which,

Figure 1 is a side elevation of the vehicle, parts being broken away.

Figure 2 is a plan view thereof, also with parts broken away.

Figure 3 is a complete plan of the device.

Figure 4 is a section taken on line 4, 4 of Figure 2.

Figure 5 is a section taken on line 5, 5 of Figure 2, and

Figure 6 is a detailed view of the rocker elements.

Referring to the drawings more in detail, numeral 1 indicates generally the vehicle toy which is provided with a single front wheel 2 and two rear wheels 3 supporting the body member 4; the front wheel 2 being carried by a steering rod 5 on the upper end of which is mounted the handle bars 6.

It is intended that the vehicle be self-propelled, and to this end I have provided a bevel gear 7 on the rear axle 8 which is adapted to cooperate with the bevel gear 9 mounted on the rear end of the longitudinally extending crank shaft 10. The shaft 10 has a bearing 11 at the rear end of the body member and a bearing 12 at the forward end thereof. This shaft is provided 55 with front and rear cranks 13 and 14 re-

spectively which are connected to the operating member in a manner to be described.

The operating member comprises a platform 15 on the lower surface of which is mounted a rocker 16 provided, of course, with a rounded lower edge 17. A channel member 18 is permanently secured to the upper surface of the body member and has its upper edge 19 curved on an arc similar to that of the rocker member. The member 16 is positioned within the channel member 18 and a pin 20 is inserted through the walls of the channel and the rocker member for holding these elements in their proper position and relation. Figures 4 and 6 of the drawing show the member 16 as provided with an enlarged aperture 23, through which the pin 20 extends. This enlargement of the aperture will permit relative movement of the pin 20 during the rocking 70 movement between the members 16 and 18. Connected to the front and rear ends of the platform 15 by means of the universal joints 21 are the downwardly extending connecting rods 22 which have their lower 75 ends joined to the cranks 13 and 14 in any well-known manner.

In the operation of the device, the child will stand upon the platform 15 with one foot on the forward end of the platform 80 and the other foot on the rear end thereof, thus permitting his weight to be shifted to the front or rear end of the platform as may be required.

This shifting of the weight of the operator will cause the platform to rock upon its rocker 16 and channel member 18 and, due to the fact that the cranks are diametrically opposed on the shaft 10, will cause the latter to turn upon its axis, thus revolving the bevel gear 9 and consequently the bevel gear 7 and shaft 8, thereby causing the vehicle to travel in whatever direction it may be guided.

From the foregoing description taken in connection with the accompanying drawings, it will be apparent that I have devised a toy which will provide both amusement and exercise for children and also one which is composed of relatively few parts which are united in a compact and durable manner so as to withstand the rough usage to which such devices are ordinarily subjected.

In accordance with the patent statutes, I have described what I now believe to be 110

the best embodiment of the invention, but I do not wish to be understood thereby as limiting myself or the scope of the invention, as many changes and modifications 5 may be made without departing from the spirit of the invention; all such I aim to include in the scope of the appended claims.

Having fully described the invention, what I claim as new and desire to secure by 10 Letters Patent is:

1. A child's vehicle, including a body member, a pair of driving wheels supporting the rear end of the body member, a crank shaft extending longitudinally of the body member, a platform extending longitudinally of the body member and pivoted thereto, a connecting rod joining a crank of the crank shaft and the platform, and a pair of bevel gears operatively connecting the crank shaft and the axle of the driving wheels.

2. A child's vehicle, including a body member, an axle and driving wheels supporting the rear end of the body member, a crank shaft extending longitudinally of the body member, a platform pivoted to the body member intermediate its ends, a connecting rod joining a crank of the crank shaft with each end of the platform, and 30 means operatively connecting the crank shaft and axle.

3. A child's vehicle, including a body member, an axle and driving wheels supporting the rear end of the body member, a crank shaft extending longitudinally of the body member, a platform pivoted to the body member, a connecting rod joining a

crank of the crank shaft with each end of the platform, a universal joint between each connecting rod and the platform and means 40 operatively connecting the crank shaft and axle.

4. In a child's vehicle, including a body member and a movable platform, means for pivotally connecting the body member and platform, said means including a channel member mounted on the body of the vehicle and a downwardly extending rocker 45 secured to the platform and positioned within the channel member.

5. In a child's vehicle including a body member and a movable platform, means for rockably mounting the platform on the body member, said means including a channel member and a rocker secured to the platform and body member, said rocker and channel member being formed with curved 55 edges.

6. A child's vehicle including a body member, an axle and driving wheels supporting the rear end of the body member, a crank shaft extending longitudinally of the body member, a platform, means for pivotally mounting the platform on the body member, said means comprising a 60 channel member having a curved edge and a rocker member having a similarly curved edge, the rocker member being positioned within the channel member, a connecting rod joining a crank of the crank shaft and the platform, and a pair of bevel gears 65 operatively connecting the crank shaft and the axle of the driving wheels.

ARTHUR C. HOWE.
